UNITED STATES PATENT OFFICE.

HIPPOLYTE PLANCHE AND LÉON PLANCHE, OF SALINS, FRANCE.

ENVELOPE.

SPECIFICATION forming part of Letters Patent No. 225,864, dated March 23, 1880.

Application filed October 4, 1879.

To all whom it may concern:

Be it known that we, HIPPOLYTE PLANCHE and LÉON PLANCHE, of Salins, Jura, in the Republic of France, have invented Improvements in Closing Bags of Paper, Linen, &c., of which the following is a specification.

This invention relates to the mode of closing paper bags intended for use in sending samples by post, and for many other uses.

10 Our invention consists in a novel form of paper blank adapted to be folded to form a paper bag, and in a bag formed from such a blank without the use of any accessory, such as gum, eyelets, ties, &c., in closing the bag.

15 In order that our invention may be well understood, we have represented on the annexed sheet of drawings, at Figures 1, 2, 3, 4, and 5, several modes of preparing sheets of paper to make sample-bags.

20 The part or lip A is to be folded and glued to form the bottom in the usual manner. The shape and the size of the bag may be changed without interfering with the mode of closing, and the lower angle can be rounded, as at B, or it may be left square. The upper part only 25 relates to the closing of the paper bag.

In Fig. 1 the angle C may be cut off and a straight cut made from D to E.

In Fig. 2 the angle C may remain, and it 30 may be folded down, following the line D F, to give more strength to the tongue. The triangle L may be then taken off, and the upper angle on the right side of the paper may be taken off, following the line G H, in

35 order to give to the bag greater lightness without decreasing the solidity of the closing.

Fig. 3 shows a combination of Figs. 1 and 2.

Fig. 4 shows another form of paper blank.

In Fig. 5 a square is cut from the right-hand corner. The closing made with this form 40 of blank does not permit the use of this bag for seeds and similar small objects; but it would be suitable for samples of certain dimensions and for business-papers, as it gives solidity as well as lightness.

Figs. 6, 7, 8, 9, and 10 refer specially to the mode of folding to obtain the proper closing of the paper bag, which we will explain in detail in reference to the blank presented,

50 Fig. 3. In this figure the letters p m p' s s' p^2 u t r p show the cut blank.

Fig. 6 shows the first fold, obtained in fold-

ing along the line v x to bring the edge t u into coincidence with the line p' p^2 .

Fig. 7 represents the second fold, obtained 55 by turning down the blank on the line p' p^2 , and securing it by glue or other substance to the first flap.

Fig. 8 shows the top right-hand corner of Fig. 7 turned down to form the triangle p v y , 60 the point being passed under the part p' s of the small flap previously turned down.

Fig. 9 represents the triangle p v y of Fig. 8 folded in half on the line v z , which brings the tongue p m p' of Fig. 8 in the position 65 shown in Fig. 9.

It remains now only to close the bag. This is effected by inserting the point m of the tongue p m p' under the previous folds, as shown by dots at Fig. 10. Thus the paper 70 bag is entirely closed, and the smallest objects cannot escape therefrom.

It is understood that this mode of folding the blank under the folds and the insertion of the tongue insure a complete closing of the 75 bag, which has not been hitherto found practicable.

If desired, the part q (shown by dots in the drawings, Fig. 6) can be strengthened by the pasting thereto a small piece of paper, linen, 80 or other suitable material.

Having now described the nature of our invention of improvements in closing bags of paper, linen, &c., and explained the manner of carrying the same into effect, we wish it to 85 be understood that we claim—

1. A paper blank for forming a paper bag having the triangular notch in one side, the opposite corner or angle removed, and the part or lip A at the lower edge for closing the 90 bottom of the bag, substantially as specified.

2. The paper bag consisting of the blank folded upon the lines v x p' p^2 , closed at the bottom by the flap or lip A, folded upon the lines p y v z , and having the point m inserted 95 under the folds previously made, substantially as specified.

In testimony that we consider the within-described improvement to be our invention we hereunto subscribe our names.

H. PLANCHE.

Witnesses: LÉON PLANCHE.
